UNITED STATES PATENT OFFICE.

WILLIAM TEEPLE, OF WATERTOWN, DAKOTA TERRITORY, ASSIGNOR TO
HIMSELF AND H. C. TROUT, OF SAME PLACE.

HAY AND STRAW BURNING STOVE.

SPECIFICATION forming part of Letters Patent No. 258,328, dated May 23, 1882.

Application filed October 6, 1881. (No model.)

To all whom it may concern:

Be it known that I, WILLIAM TEEPLE, of Watertown, in the county of Codington, Dakota Territory, have invented a new and useful Improvement in Hay and Straw Burning Stoves, of which the following is a full, clear, and exact specification.

Reference is to be had to the accompanying drawings, forming part of this specification, in which similar letters of reference indicate corresponding parts in all the figures.

Figure 1 is a sectional side elevation of my improvement. Fig. 2 is a sectional plan view of the same, taken through the line *x x*, Fig. 1. Fig. 3 is a side elevation of the feed-bucket, part being broken away. Fig. 4 is a plan view of the same, partly in section through the line *y y*, Fig. 3. Fig. 5 is a sectional elevation of a part of the burner. Fig. 6 is a sectional plan view of a part of the bucket, taken through the line *z z*, Fig. 5, showing a keeper for the fastening-rod. Fig. 7 is a sectional plan view of a part of the bucket, taken through the line *v v*, Fig. 5, showing a keeper for a strap.

The object of this invention is to provide an effective means for burning hay and straw for heating and cooking purposes, and also to promote convenience in supplying the burner with fuel.

A is the base of the burner, which is made square and of a length and width about two inches greater than the diameter of the outer cylinder, B, and eight inches deep, to afford space for a large ash-pan. The base A is provided with feet C in the ordinary manner, and its front is formed of two doors, D, to allow the ash-pan to be conveniently put in and taken out.

The cylinder B is made of sheet-iron, and is about two feet in diameter and two and a half feet in height.

To the upper edge of the cylinder B is attached a ring-cap, E, which is provided with an inner flat cover, F, and an ornamented outer cover, G. The covers F G are pivoted near one side to the ring-cap E, so that they can be swung to one side to allow fuel to be conveniently introduced.

In the top of the base A is formed an opening of a diameter nearly equal to the interior

diameter of the cylinder B, and across which extend cross-bars H to support the inner cylinder, I, and the grate J. The inner cylinder, I, is formed of upright parallel bars connected at their upper and lower ends by rings, as shown in Figs. 1 and 2. The cylinder I is kept in place by lugs or shoulders formed upon or attached to the bars H. The inner cylinder, I, is about twenty inches in diameter and of about the same height as the outer cylinder, B, so that its upper edge will rest against a shoulder or flange of the ring-cap E. With this construction a draft-space will be formed all around the fuel contained in the inner cylinder, so that the draft cannot become obstructed. The grate J is pivoted at its center to the cross-bars H, and is provided with upwardly-projecting pins or points K, two inches (more or less) in height, to rake off the ashes from the bottom of the burning mass of hay or straw. The inner cylinder, I, and the grate J can each be vibrated to shake down the ashes by means of a lever introduced through a draft-opening in the lower part of the cylinder B, which opening is closed by a sliding damper, L, so that the draft can be regulated as may be required.

In the cylinder B, a little above the damper L, is formed an opening, closed by a door, M, for convenience in lighting the fire.

In the cylinder B, near its upper edge, is formed a small opening, closed by a sliding or rotating damper, N, to give a sufficient draft to carry off the smoke and developed gases when the lower damper, L, is closed.

O is the feed-bucket, which is open at top and bottom, and is formed of a plate of sheet metal bent into cylindrical form, with its edges overlapped.

To the outer edge of the plate of the bucket are attached the ends of three straps, P, which pass through slots or notches in an upright rod, Q. The rod Q slides in keepers R, attached to the inner part of the plate of the bucket at such a distance from its edge as to be out of the way of the outer edge when the bucket is contracted. The keepers R are arranged in pairs above and below the straps P to hold the said straps in place. The free ends of the straps P pass through keepers S, attached to

the side of the bucket O, to keep the said ends close to the side of the said bucket. The free ends of the straps P can be bent outward, or can have pins attached to them to serve as 5 stops to prevent the said straps from drawing out of the said keepers and to prevent the bucket from expanding too much. In the upper edge of each of the straps P is formed a notch, into which the rod Q (or shoulders or 10 studs upon the said rod) drops when the bucket O is contracted to the desired point, to lock the said bucket in that position.

To the middle part of the rod Q is attached an outwardly-projecting pin, T, to strike against 15 the ring-cap E and raise the rod Q from the notches in the straps P, allowing the bucket to expand and dropping the charge of fuel into the cylinder I.

In using the burner the hay or straw is 20 packed into the feed-bucket O by hand, and when the fire is to be started or replenished the covers G F are swung back and the filled bucket is inserted in the cylinder I until the pin T strikes the cap E and raises the rod Q, 25 allowing the bucket to expand and drop the fuel into the said cylinder. The top of the fuel is then pressed down a little, and the covers F G are closed. The bucket O is provided with a strap-handle, U, for convenience in 30 handling it. The ends of the handle U are hooked upon knobs or hooks V, attached to the opposite sides of the top of the said bucket, as shown in Fig. 3.

In the upper part of the cylinder B is formed 35 an opening, with which is connected the smoke-pipe W, to conduct the smoke and other gaseous products of combustion to the chimney.

I have described my improvement as applied to a heating-stove, but do not limit myself to that use, as it can be applied with equal 40 advantage to a cooking-stove.

Having thus described my invention, I claim as new and desire to secure by Letters Patent—

1. The outer and inner cylinders, B I, the latter supported on cross-bars H of the former, 45 in combination with the flanged cap E, having inner and outer covers, F G, pivoted thereto, as shown and described.

2. In a hay and straw burning stove, an expandible fuel-bucket, O, made substantially as 50 herein shown and described, and consisting of a cylinder which is capable of being expanded after its introduction within the fire-chamber, so as to discharge the fuel, as set forth.

3. In a hay and straw burning stove, the 55 combination, with the expandible bucket O, of the notched straps P and the sliding lock-rod Q, substantially as herein shown and described, whereby the bucket can be readily fastened and unfastened, as set forth.

4. In a hay and straw burning stove, the combination, with the bucket-locking rod Q, of the projecting pin T, substantially as herein shown and described, to strike against the top of the stove, unlock the bucket automatically, 60 and discharge the fuel when the filled bucket is inserted in the stove, as set forth.

WILLIAM TEEPLE.
